GATE VALVE

William E. Lowrey and Clifford E. Anderson, Houston,
and Ronald A. Gulick, Sugar Land, Tex., assignors to
ACF Industries, Incorporated, New York, N.Y., a
corporation of New Jersey

Filed Apr. 26, 1965, Ser. No. 85,149

Term of patent 14 years

(Cl. D91—3)

FIG. 1.

FIG. 2

FIGURE 1 is a perspective view of a gate valve, showing our new design.

FIGURE 2 is a plan view of the gate valve of FIGURE 1.

The opposite side of the valve is a substantial duplicate of the view illustrated in FIGURE 1 except that the substantially horizontal projection at the lower right portion of FIGURE 1 and the two projections and horizontal configuration located centrally of vertical cylindrical portion of FIGURE 1 will not appear in an opposite view.

The base of the valve of FIGURE 1 is formed by an open cylindrical flange fixed to the closed curved bottom wall of the valve.

This is a continuation-in-part of our co-pending design application, Serial No. 78,193 filed January 14, 1964, and now abandoned.

We claim:

The ornamental design for a gate valve, as shown and described.
